US00D420652S

United States Patent [19]

Izaki

[11] Patent Number: Des. 420,652

[45] Date of Patent: ** Feb. 15, 2000

[54] **MAGNETIC DISC MEMORY DEVICE FOR ELECTRONIC COMPUTERS**

[75] Inventor: **Kenzo Izaki**, Chiba, Japan

[73] Assignee: **Kabushiki Kaisha Toshiba**, Kawasaki, Japan

[**] Term: **14 Years**

[21] Appl. No.: **29/096,224**

[22] Filed: **Nov. 6, 1998**

[30] **Foreign Application Priority Data**

May 18, 1998 [JP] Japan 10-13966

[51] LOC (7) Cl. **14-02**

[52] U.S. Cl. **D14/107**

[57] **CLAIM**

The ornamental design for a magnetic disc memory device for electronic computers, as shown and described.

DESCRIPTION

FIG. 1 is a top, front and right side perspective view of a magnetic disc memory device for electronic computers showing my new design;

FIG. 2 is a front elevational view thereof;

FIG. 3 is a right side elevational view thereof, the left side elevational view being a mirror image;

FIG. 4 is a top plan view thereof;

FIG. 5 is a bottom plan view thereof; and,

FIG. 6 is a rear elevational view thereof.
